UNITED STATES PATENT OFFICE.

JOSEPH A. WADDELL, JR., OF SCRANTON, PENNSYLVANIA, ASSIGNOR TO SPENCER HEATER COMPANY, OF SCRANTON, PENNSYLVANIA, A CORPORATION OF PENNSYLVANIA.

STEAM AND HOT-WATER FURNACE.

1,356,028.

Specification of Letters Patent.

Patented Oct. 19, 1920.

Application filed October 14, 1916. Serial No. 125,651.

To all whom it may concern:

Be it known that I, JOSEPH A. WADDELL, Jr., a citizen of the United States, residing at Scranton, in the county of Lackawanna and State of Pennsylvania, have invented certain new and useful Improvements in Steam and Hot-Water Furnaces, of which the following is a specification.

This invention relates primarily to fire boxes for receiving and holding fuel such as coal, during combustion. It is designed for and is herein illustrated in connection with furnaces for heating water that is to be circulated as hot water, or in the form of steam in connection with heating plants for buildings. But the invention is not restricted to this particular use.

One object of the invention is to confine the fuel in a form and under conditions that will insure complete distillation of its combustible constituents, to which end, one feature of the invention consists in confining the fuel, during combustion, in one or more vertical columns of longitudinal dimension determined mainly by the capacity to be given to the furnace, of a vertical dimension suitable to insure complete burning of the fuel and its delivery into the form of ash at a dumping point at the lower end of the column, and of a transverse dimension that will insure maintenance of an effective fire bed without excessive obstruction to draft; the column of burning fuel being confined between walls which, while preventing lateral escape of the fuel, will afford a free passage of air transversely through the fuel column and into the heat-absorbing spaces of the boiler; this condition being preferably maintained throughout the vertical column of fuel and being realized preferably by confining the fuel between two substantially vertical walls having air passages extending through them; walls of the air passages being inclined downwardly to resist escape of the fuel through the air passages.

Another object of the present invention is to provide for discharging at will, a measured quantity of the lowermost stratum or portion of the column of material, in the fire box, after it has reached the condition of ash, to which end, another feature of the invention consists in providing a bottom closure for the fire box in the form of a valve or cut-off that permits ashes of a desired

quantity to escape at a stroke of the valve; this feature being preferably realized through means of a clam shell or twin valve construction that first opens to admit the measured quantity, and then closes to intercept the remaining column of material while permitting the measured-off quantity to discharge.

A further object is to arrange for more efficient operation of a fire box embodying the principles above described, to which end, another feature consists in combining two columns of fuel in spaced relation, with a common air flue between them, so that opposed radiation from their intake walls effectively heats the incoming air, while radiation, in addition to the discharge of burning gases from their discharge walls, may act upon the heating surfaces; the intake walls, as well as the air flue formed between them, being preferably continued vertically to correspond with the maintained fire bed, and this air flue being preferably closed at top by a water cap supported upon the spaced walls and having connection, as for instance, at its respective ends, with the circulation system of the boiler, so that it may add its heat-absorbing capacity to that of the other absorbing units of the boiler.

A further object is to provide for an efficient fuel supply that will at all times maintain the full supply of fuel to the fire bed, to which end, a further feature consists in superimposing upon the legs of the fire box, and preferably above the water cap of the intake flue, a fuel reservoir from which fuel will pass by gravity into the legs of the fire box and maintain the columns of fire bed in the required and compact condition for effective burning; the magazine thus provided being preferably formed with a restricted throat which may be realized by inwardly deflecting a wall or walls of the magazine, and in the duplex form, forming and locating the water cap so that it will coat with the walls of the magazine in developing the restricted throats.

Further objects relate to conditions through which to realize, effectively, the several principal objects above enumerated, to which ends, further features consist in utilizing circulating connections of the boiler as supports for the walls of the fire

box; and constructing these walls in subdivisions or sections which adapt them for easy insertion and removal, as well as replacement in the event of destruction.

- 5 Finally, an object of the invention is to provide an organization of the magazine, fire box and heat-absorbing elements of the furnace, in a manner to bring them into relationship that will be effective for realizing 10 their several objects, conserving the heat, and transferring it in maximum degree to the water or circulating medium.

In order that the invention may be fully understood, two illustrative embodiments 15 will now be described with reference to the accompanying drawings, in which—

Figure 1 is a vertical transverse section of a boiler made up of cast metal sections, to which one form of the present invention is 20 applied.

Fig. 2 is a vertical longitudinal section on the line 2—2 of Fig. 1.

Fig. 3 is a vertical longitudinal section on the line 3—3 of Fig. 1.

25 Figs. 4 and 5 are detail perspective views of units which go to make up the walls on the discharge and intake sides of the fire bed, respectively.

Fig. 6 is a vertical transverse section of a 30 boiler of tubular type having the present invention applied thereto.

Referring to Figs. 1 to 5, 1 represents a magazine, 2 the fire boxes, 3 the combustion chamber, and 4, 4^a, 4^b the circulating flues 35 of a cast section boiler, made up preferably of section units 5, 5^a, brought into abutment at 6 and constructed with suitable water passages in their walls, as well as flanges through which the sections are brought into 40 abutment in building up the furnace.

According to the present invention, air entering at the base 7 of the furnace passes upwardly through a flue 8, and thence laterally through air passages 9 and across the 45 column of fuel in the fire boxes 2, whence it escapes through the openings 10 into the combustion chambers 3. Each of the fire boxes 2 is closed at the bottom through means of a dumping valve or grate, preferably of the clam shell type composed of 50 members 11^a pivoted at 11^b and forced to move in unison by means of gear wheels 11^c, so that when oscillated in a direction to open at the top, they close together at the 55 bottom and admit a measured quantity of ash, and when returned to closed position at the top, they discharge the measured quantity of ash thus withdrawn and so provide a means for getting rid of the consumed portion of the fuel and excluding live 60 coals, without disturbing the column of fire bed. In order to operate with greater efficiency, the fire boxes 2 are arranged in duplicate on opposite sides of the air flue 8 with 65 similar intake passages 9 and discharge pas-

sages 10 for the air, and in order to close the air flue 8, a water cap 12 is supported on the walls of the flue 8.

The magazine 1 above the fire boxes 2 preferably has its walls 1^a deflected inwardly 70 to develop constricted throats 1^b in connection with the water cap 12, and the latter is formed with inclined upper surfaces to direct the fuel to these throats.

The walls 9^a, may be constructed in various ways. Preferably, they are built up of sections; the wall 9^a being formed of sections 9^c with recesses that form the air passages 9 through them, and with seats 9^d at their ends that conform to the water tubes 80 13, 13^a, by which they are supported, or to the convex lower edges 12^a of the water cap 12 supported upon them. By this method, standard units may be employed for building up different sizes of furnace and parts 85 may readily be assembled in setting up the boiler, or replaced when burned out. The lower supporting tubes 13^a are preferably united with tubes 13^b, so as to provide walls 90 for confining the ash immediately above the dumping valves. The walls defining the discharge passages 10 are built up of sections formed with seats 10^c at the ends thereof to seat against the sustaining ledges 10^d on the boiler sections 5, 5^a, the plates 10^e 95 of the wall sections being provided with mortises 10^f for receiving the plates 10^e whereby the latter may be positioned to reflect the fuel inwardly away from the combustion chambers 3.

From the foregoing construction, it will be seen that air rising through the central flue 8 passes transversely through the respective legs of the fire bed, keeping up combustion therein and causing the burning 100 gases to pass into the combustion chambers 3, when they escape through the circulating flues 4, 4^a, 4^b in the manner well known in cast sectional boilers. Heat radiated from the legs of the fire bed raises the temperature of the incoming air to support combustion and thus increases efficiency of burning. Heat is also radiated through the discharge passages 10 toward the heating surfaces of the boiler units and thus adds to 105 the heating effect of the burning gases, the plates 10^e being inclined substantially as shown, which presents them about perpendicularly to the angle of repose of the fuel, and being spaced vertically so far as practicable without permitting fuel, which settles 110 downwardly past the lower edge of one plate, flowing outwardly beyond the upper edge of the next lower plate in assuming its 115 said angle of repose.

As will be understood upon reference to Fig. 6, the invention is not limited in its application to cast sectional boilers, but may be used with equal advantage in a boiler 120 having water tubes 14 with concentric fire 125 tubes 15.

tubes 15 and drums 16, or other equivalent water-circulating connections. In providing a magazine in this type of boiler, baffles 17 with water tubes 17^a together form 5 a wall extending upwardly from the walls formed by the plates 10^a and 10^b to the drum 16. Otherwise, the construction corresponds in substance to that described with reference to Figs. 1 to 5. As will be seen from Fig. 10 6, constricted throats 1^b may be provided in this form of boiler without inclining the walls inwardly toward the water cap 12.

When in the foregoing specification and in the subjoined claims, I use the expression "vertical fire box" or "vertical walls" 15 in reference to the walls which define said fire box, I do not wish to have it understood that these terms are to be taken literally, but merely indicate, generally, a fire box or the 20 walls defining the fire box which extend upwardly at such angles or approach the vertical to such an extent as to present the problem of confining the fire bed against falling away laterally; in other words, positioned to introduce a distinct departure 25 from mere grates upon which the fuel will rest, or to which it will lie by gravity. It is obvious that while the disposition of the fire box or twin fire boxes herein illustrated 30 is preferred, the principle of my invention would not be departed from by somewhat inclining these fire boxes or either of them in either direction to the vertical.

I claim:—

35 1. A furnace comprising a central magazine with depending side walls, flues and heat absorbing surfaces on either side of said magazine, combustion chambers located on

the outer sides of the depending magazine walls, and a pair of vertical fire boxes located beneath and served in common by said magazine; said fire boxes comprising outer walls in vertical alinement with the depending side walls of the magazine and vertical inner walls spaced apart to leave a central 40 air flue between them; said inner and outer fire-box walls having air passages that develop a horizontal draft through the fire boxes; and said fire boxes being adapted to be closed at top by the body of coal in the 45 magazine, and having suitable bottom closures.

2. In a furnace, the combination of a magazine, and a pair of vertical fire boxes located beneath and served in common by 50 said magazine, said fire boxes having spaced inner walls which leave a vertical air flue between the fire boxes and apertured outer walls, and said furnace being provided with combustion chambers laterally disposed with 55 reference to the outer walls of the fire boxes.

3. In a furnace, the combination of a magazine, a pair of vertical fire boxes located beneath and served in common by said magazine, said fire boxes having inner walls 60 spaced apart to provide an air supply flue between them and apertured to admit air from the flue to the fire boxes, apertured outer walls to the fire boxes whereby horizontal draft is permitted through the fire 65 boxes, and a deflecting cap surmounting the inner spaced wall of the fire boxes and forming an upper end closure for the air flue.

The foregoing specification signed at Scranton, Pennsylvania.

JOSEPH A. WADDELL, JR.
